FIG. 1

FIG. 2

FIG. 3

FIG. 4

FIG. 5

FIG. 6

FIG. 1 is a front perspective view of a slide viewer showing my new design, with the screen in collapsed condition;

FIG. 2 is a rear perspective view thereof;

FIG. 3 is a bottom plan view thereof;

FIG. 4 is a front perspective view of the viewer with the screen in open condition;

FIG. 5 is a side elevational view thereof; and

FIG. 6 is a rear elevational view thereof.

Stippling is employed to indicate contrast in appearance.

The dominant feature of my design resides in the combination on a slide viewer of the closed configuration as shown in FIGS. 1 and 2 of the large base portion having similar relative height as the recessed central portion and a top portion having lateral dimensions substantially equal

to those of the base but a height substantially less than the base and central portion.

The essential features of my design are shown in full lines.

I claim:

The ornamental design for a slide viewer or similar article, substantially as shown and described.
